UNITED STATES PATENT OFFICE.

FRANCIS H. HARDON, OF NEW YORK, N. Y., ASSIGNOR OF ONE-HALF TO FRANK
PALLADINO, OF NEW YORK, N. Y.

VALVE FOR COMPRESSED-AIR TRANSOM-OPERATORS.

1,361,381.

Specification of Letters Patent.

Patented Dec. 7, 1920.

Application filed October 20, 1915. Serial No. 56,982.

To all whom it may concern:

Be it known that I, FRANCIS H. HARDON, a citizen of the United States, residing at New York, in the county of New York and State of New York, have invented certain new and useful Improvements in Valves for Compressed-Air Transom-Operators; and I do hereby declare the following to be a full, clear, and exact description of the invention 10 such as will enable others skilled in the art to which it appertains to make and use the same.

The invention relates to improvements in transom operating devices.

15 The object of the present invention is to provide an improved valve of simple, practical and comparatively inexpensive construction for controlling the admission of air to and the escape of air from a cylinder, 20 in which is pivotally mounted a piston adapted to be attached to a transom operating mechanism so as to enable a transom to be easily opened or closed without manual labor and by simply operating a push 25 button.

With these and other objects in view the invention consists in the construction and novel combination and arrangement of parts hereinafter fully described, illustrated in 30 the accompanying drawings and pointed out in the claims hereto appended, it being understood that various changes in the form, proportion and minor details of construction may be resorted to without departing 35 from the spirit or sacrificing any of the advantages of the invention.

In the drawings—

Figure 1 is an elevation of the device constructed in accordance with this invention 40 and shown applied to a door frame and transom.

Fig. 2 is a vertical sectional view taken substantially on the line 2—2 of Fig. 1, the transom operating device being shown in 45 elevation,

Fig. 3 is an elevation of the actuating mechanism,

Fig. 4 is a central vertical sectional view through the actuating mechanism showing 50 the valves in position for raising the piston.

Like numerals of reference designate corresponding parts in the several figures of the drawings.

In the accompanying drawings in which 55 is illustrated the preferred embodiment of

the invention, 1 designates a transom hinged at the top at 2 and provided at the bottom at one end with a horizontally projecting arm 3 having an inner attaching portion 4 secured by screws or other suitable fastening devices to the transom as clearly shown in Fig. 1. The horizontal arm 3 which extends outwardly from the transom is connected by a link 5 with a vertically movable rod 6 operating in a guide 7 and actuated by the means hereinafter described for opening and closing the transom. The guide which may be of any preferred construction is mounted on the exterior of the door frame or casing 8 and the vertically movable rod 70 or member 6 extends above and below the horizontal arm 3. The link 5 which extends downwardly and inwardly from the horizontal arm 3 is pivoted at its upper and lower ends 9 and 10 to the said arm 3 and to the vertically movable rod or member 6. The vertically movable rod 6 is suitably secured at its lower end by nuts 11 or other suitable fastening devices to a horizontal arm 12 which is carried by a vertically movable piston rod 13. The piston rod 13 which extends upwardly from a piston head 14 is secured at its upper end in an opening in the inner end of the arm 12 by a suitable fastening device 15 and the cylinder 16 in 85 which the piston operates is provided with upper and lower attaching lugs 17 and is arranged within the door frame or casing as clearly shown in Fig. 2 of the drawings. The cylinder which may be of any preferred 90 construction is provided at the upper end adjacent to the head 18 with a vent opening 19 for the escape of air when the piston moves upwardly and to admit air to the cylinder when the piston moves downwardly. The piston is equipped with suitable packing rings and compressed air is admitted to the lower end of the cylinder through a small tube 20 connecting the cylinder with a valve casing 21 arranged vertically and connected at its lower end with a compressed air supply pipe or tube 22.

The valve casing is provided with an upper exhaust or outlet opening 23 and it has a valve seat 24 formed in a partition 25 and 105 receiving a valve 26 which controls the exhaust port or outlet. The valve casing is also provided with a feed port 27 formed in a partition 28 and receiving a valve 29 which controls the admission of compressed 110

air to the cylinder. The valve casing is provided at the back with threaded openings 30 located diametrically opposite the valve seat and normally closed by threaded plugs 31. The openings are adapted to afford access to the valve seat to enable the same to be ground and they permit the valve to be introduced into and removed from the valve casing. The valves which 5 are tapered are seated at the pressure side so that the pressure will hold the supply or inlet valve firmly against its seat when the exhaust valve is opened and will also operate to hold the exhaust valve firmly 10 against its seat when the inlet valve is opened. The valves are provided with stems 32 and 33 extending outwardly through flanged apertures of the valve casing and connected to the arms of a lever 34 which causes the valves to move in unison 15 so that when one valve is opened the other will be closed. The flanged apertures 35 are provided with caps 36 having suitable packing and the lever 34 is fulcrumed at 37 to the outer end of a horizontally disposed 20 bracket arm 38 consisting of a pin and having its inner end 39 threaded into an opening in the front of the valve casing. The outer ends of the stems of the valves are 25 equipped with suitable heads or buttons 40 and 41 which are designed in practice to bear a suitable word for indicating the character of the valve. The door frame or casing is provided at the valve casing with a 30 face plate 42 having openings for the passage of the stems of the valve and adapted to be readily removed to afford access to the mechanism.

The valve is especially adapted for use 35 in connection with transom operating devices for apartments, office buildings, hotels and similar structures which are often provided with air compressors and it will only necessitate an additional storage tank and 40 pipe connections which may be exceedingly small as only a very small amount of compressed air will be necessary for swinging a transom upwardly and gravity will return the transom to its closed position when 45 the feed or supply valve is closed and the exhaust or outlet valve is opened. The pipings may be easily concealed in the door frames or casings and the air discharged from the cylinder through the exhaust port 50 may be permitted to escape at any point and need not be piped to the outside atmosphere. Also the cylinder may be conveniently constructed of heavy brass tubing or similar material and need not consist of a casting

when it is desired to construct a cheap equipment. 60

While the transom is shown hinged at the top, it may be pivotally mounted centrally of its ends similar to an ordinary transom. 65

What is claimed is:—

1. A valve for controlling the admission of air to and its escape from the cylinder of a transom operating device, comprising a casing having a discharge port at one end communicating with said cylinder and having an intake port at its other end, said casing also having an exhaust port in one of its side walls adjacent the discharge end thereof, a partition formed within the casing about the intake port to provide an air intake chamber, said partition being provided with an opening having a tapered wall to provide a valve seat facing into the intake chamber, a tapered valve head co-operating with said seat and adapted to be normally held to said seat by the air pressure within said intake chamber, a second partition formed in the casing about said exhaust port to provide an air exhaust chamber, said second partition being provided with an opening having its wall tapered to provide a valve seat facing into said casing, a second tapered valve head co-operating with said second valve seat and adapted when said first valve head is unseated and air under pressure is in the casing to be held to its seat by such pressure, a valve stem connected to each of said valve heads, said valve stems passing through one side wall of the casing, and a connection between said valve stems adapted, when one valve stem is moved in one direction, to move the other valve stem in the reverse direction. 80

2. A valve for controlling the admission of compressed air to and its escape from the cylinder of a transom operating device, comprising a casing having an inlet port, an outlet port and an exhaust port adjacent the outlet port, inlet and exhaust valves controlling the inlet and exhaust ports, each valve being adapted when closed to be held in such position by the air pressure within the casing, and a pivoted lever connected to the valves to cause one valve to be closed when the other is opened and to permit the air pressure against the closed valve to hold the other valve opened. 100

In testimony whereof I affix my signature in presence of two witnesses.

FRANCIS H. HARDON.
